ANIMAL FIGURE

Patsie Sinkey Norrick, Seattle, Wash.

Application June 2, 1955, Serial No. 36,339

Term of patent 14 years

(Cl. D34—2)

Fig. 1 is a perspective view of an animal figure showing my new design, as viewed from a position facing a portion of the left side and a portion of the front thereof;

Fig. 2 is a side view in elevation of the same; and

Fig. 3 is a front view in elevation of the same.

I claim:

The ornamental design for an animal figure, substantially as shown.
